(57) **CLAIM**

The ornamental design for a step counter, as shown.

DESCRIPTION

FIG. 1 is a perspective view of the step counter of this invention;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a perspective view of this invention in rear view; and,

FIG. 9 is a perspective view of the invention in open position.
